UNITED STATES PATENT OFFICE.

CHARLES CALVERT LAMB, OF CHICAGO, ILLINOIS, ASSIGNOR OF ONE-HALF TO
WILLARD M. McEWEN, OF CHICAGO, ILLINOIS.

RAIL-JOINT.

1,113,127.

Specification of Letters Patent.

Patented Oct. 6, 1914.

Application filed March 13, 1913. Serial No. 753,907.

To all whom it may concern:

Be it known that I, CHARLES C. LAMB, a citizen of the United States, and a resident of Chicago, in the county of Cook and State 5 of Illinois, have invented certain new and useful Improvements in Rail-Joints; and I do hereby declare that the following is a full, clear, and exact description thereof, reference being had to the accompanying 10 drawings, and to the letters of reference marked thereon, which form a part of this specification.

This invention relates to rail joints of that kind especially adapted for street-railway 15 rails, consisting of a joint bar adapted to support the meeting ends of the rails, and provided with means by which the ends of the rails are secured thereto, and it includes, as one feature thereof, improved features of 20 construction in means for rigidly and securely holding the meeting ends of the rails accurately in alignment with each other, and for rigidly supporting the laterally extending flanges of the rail-heads, which are 25 grooved to receive the wheel-flanges, from downward yielding or deflection at such meeting ends of the rails.

One of the objects of the invention is to provide in connection with a one-piece joint 30 bar having longitudinal, side members extending at opposite sides of the rails, means adapted to operate with a wedge action for clamping the ends of the rails in the joint bar, and also for exerting an upward pressure 35 on the laterally extending grooved flanges of the rails, in a manner to sustain the adjacent meeting ends of such flanges in the same horizontal plane, and to thereby lessen the liability of the said meeting ends 40 of the flanges from being unequally depressed or thrown out of line with each other under the action of passing loads.

The invention consists in the matters 45 hereinafter described and pointed out in the appended claim.

In the accompanying drawings illustrating my invention—Figure 1 is a perspective view of a rail joint embodying my invention; Fig. 2 is a view of the joint, partially 50 in elevation and partially in vertical section, to be taken upon line 2—2 of Fig. 4; Fig. 3 is a horizontal section taken upon line 3—3 of Fig. 4; Fig. 4 is a transverse section of the joint, taken upon line 4—4 of

Fig. 3; Fig. 5 is a cross sectional view of 55 the joint, taken upon line 5—5 of Fig. 3.

As shown in the accompanying drawings, the track-rails 5, 5 are of the type commonly used for street railways, and consist each of a deep central web 5^a, horizontal 60 base flanges 5^b, 5^b, and a head 5^c, provided at one side thereof with a laterally extending flange 5^d provided with a groove in its top surface for the flanges of the car-wheels. The meeting ends of said track-rails 5, 5 65 are supported and held in place by means of a one-piece joint bar, consisting of a horizontal base-plate 6 and longitudinally extending side members 7 and 8, embracing parts 7^a, 8^a, which extend inwardly over the 70 base flanges of the rails, vertical parts 7^b, 8^b, which extend upwardly at the sides of and parallel with the web 5^a of the rail, and outwardly extending upper members 7^c, 8^c, which are located beneath the head 5^c and 75 lateral flange 5^d of the rails. The base plate 6 is provided with a longitudinally extending, depending web 9, having at its lower margin outwardly extending, horizontal flanges 9^a, 9^a, said web and flanges 80 forming a stiffening girder for the joint-bar, adapted to extend between the two ties on which the ends of said joint-bar rests or is supported. The said web 9 and flanges 9^a, 9^a are connected at the center and ends 85 thereof with transverse, integral flanges 9^b, 9^b and 9^c, 9^c. Adjacent to its ends exterior to the ties, the base-plate 6 is provided with depending transverse flanges 9^d, 9^d, and with central longitudinally extending web members 9^e joining the same with the end portions of the base-plate which extend beyond the said transverse flanges.

In the case of one of the side members 7, the downwardly, inwardly and upwardly 95 facing surfaces thereof, indicated by 10, 11 and 12 respectively, are shaped to conform to the adjacent upwardly, outwardly and downwardly facing surfaces of the webs, base flanges and heads of the rails, and have 100 bearing contact with said surfaces of the rails when the latter are in place in the joint bar. In the case of the other longitudinal member 8, the downwardly, inwardly and upwardly facing surfaces thereof, indicated by 13, 14 and 15, respectively, are 105 spaced from the adjacent surfaces of the base flanges, webs and top flanges of the

rails. Said downwardly, inwardly and upwardly facing surfaces of the said member 8 are inclined longitudinally from end to end of the said side member 8 so as to leave 5 tapered spaces between the parts 8^a, 8^b and 8^c of said member 8 and the adjacent surfaces of the base flanges, webs and top flanges 5^a of the rails. Inserted between said member 8 and the ends of the rails is 10 a wedge piece 16, which is made generally of U-shape in cross section and consists of a base member 16^a, an upright member 16^b and a top member 16^c; these members being made in one piece or integral with each 15 other. All three of the members of said wedge piece are tapered from end to end, the tapered form being given to such parts by making their downwardly, outwardly and upwardly facing surfaces inclined to 20 correspond with the inclined surfaces 13, 14 and 15 of the member 8.

In order to hold the parts or members of the side members 7 and 8 from bending or yielding relatively to each other, and especially to prevent any downward yielding of 25 the top members 7^a and 8^a of said side members, said side members are provided with a plurality of transverse stiffening flanges 7^d and 8^d, which are made integral with the said 30 parts or members and are spaced apart longitudinally of the joint-bar. As illustrated, three of these stiffening flanges are employed, one located at the center and the other two at the ends of the said side members 7 and 8. The said longitudinal side 35 members 7 and 8 of the joint-bar are made substantially shorter than the length of the bar itself and preferably only slightly longer than the distance between the ties on 40 which the joint-bar is supported. The wedge member 16 is made slightly longer than the side member 8 engaged thereby and is provided at its thicker end, by preference made integrally therewith, a trans- 45 verse arm 17, which extends outwardly from the outer margin of the base member 16^a over the top surface of the base-plate 6 and projects beyond the outer lateral margin of said base-plate. The lower surface of said 50 arm 17, in its part exterior to the base-member 16^a and the side margin of the base flange of the rail, is horizontal and adapted to rest or bear against the marginal portion of the top surface of the base-plate. In the 55 outer end of said arm is formed a spike hole 17^a. Said arm 17, thus arranged, is adapted to come over or above one of the ties 18, 18 (Fig. 2), and when the wedge member is inserted in place, a spike, as indicated by 20, is inserted through the spike 60 hole 17^a and driven into the tie so as to rigidly and securely hold the wedge member from endwise movement. The spike thus driven through the arm 17 serves not only 65 to hold the wedge member from movement

but also to aid in holding the joint-bars to the ties. As shown in the drawings, three other spikes 21, 21, 21 are driven into the ties 18, 18, with their heads engaged with the side margins of the ends of the base-plate. 70

In connection with the wedge member arranged as described, I have shown in the accompanying drawings, track bolts 22, 22, which are inserted horizontally through the 75 side members 7 and 8, the upright member 16^b of the wedge piece and the webs of the rails, the said track bolts being provided with the usual nuts 22^a by which they may be tightened and the upper margins of the 80 side members 7 and 8 are held from spreading apart, or away from the rails, under the action of the wedge member when the latter is inserted or driven into its place. The bolt holes 7^e and 8^e, formed in the side members 7 and 8 for the insertion of the bolts, will be preferably slightly elongated longitudinally of said members in order to permit the relative endwise movement of the rail 85 ends under the expansion and contraction of the rails due to changes in temperature. The bolt holes 5^e, 5^e in the webs of the rails will preferably be made circular, but only slightly larger in diameter than the track 90 bolts. The bolt holes 16^d, 16^d in the upright 95 member 16^b of the wedge piece are elongated longitudinally of the wedge member, to such an extent as required to provide for any possible endwise movement or shifting of the wedge member when driven into bearing 100 contact with the rail and joint-bar.

In the assembling of the parts of a rail-joint, embracing the features of construction shown in the drawings, the ends of the rails will be inserted in the longitudinal slot or 105 opening of the joint-bar and brought into proper position, and the wedge member will then be driven tightly into place so as to clamp the ends of the rails rigidly and firmly between the side members, and against the base-plate of the joint-bar. The track bolts will then be inserted and the nuts thereon screwed up so as to draw toward 110 each other the upper margins of the side members 7 and 8. By the upward pressure 115 of the top flange or member 16^c of the wedge piece against the under surface of the lateral, grooved flanges 5^a of the rails, the said flanges will be rigidly sustained or supported at their meeting ends. It is well understood that those parts of street railway rails 120 which are first to weaken and give way, are the meeting ends of the grooved flanges, which, by reason of the elasticity of the metal and the lack of direct support therefor, are liable to yield or be deflected downwardly, under the pressure of the passing wheels, in such manner that when the flange is depressed or yields downwardly at the 125 end of one rail, before the wheel acting 130

thereon reaches the adjacent end of the next rail in advance, the wheel will strike with a hammer blow the end of the flange which is not so depressed, and such hammering action, as well as the downward flexure or yielding of the grooved flanges at both of the meeting rail-ends, will bring about a rapid distortion and weakening of such flanges under the constant action of the vehicle wheels. It will, of course, be understood that in applicant's construction illustrated, the upper flange 16^c of the wedge-piece exerts a wedging action between the grooved flanges 5^d of the rails and the upper, rigidly supported member 8^c of the side member 8, so that the said upper flange 16^c while it exerts a constant upward pressure on the rail flange 5^d, is itself rigidly or unyieldingly sustained or supported by the side member 8 of the joint-bar, the upper member 8^c of which is rigidly sustained by the lateral stiffening flanges 8^d, 8^d. Moreover, notwithstanding that the three parts 25 of the wedge-piece, to wit, the base-member 16^a, the upright member 16^b and the top member or flange 16^c, are made integral with each other, the top flange 16^c being relatively thin and capable of a certain degree of lateral flexure, is adapted to adjust itself to the surfaces of the rail-flange 5^d and the top member 8^c, between which it is inserted, so that said flange 16^c will always act to maintain an upward pressure against the rail flange above the same, and prevent downward yielding of said rail flanges. It is to be understood, however, that, without regard to the use of the track bolts, the wedge-piece made as described, namely, with integrally connected base, upright and top members, in itself affords important advantages in connection with the joint-bar made as described, it being understood that when the wedge-piece is driven into place, it serves to force or press the base-flanges of the rail 40 downwardly against the base-plate and at the same time to press or clamp the web of the rail against the opposing side member 7, and to also exert an upward pressure on the under surface of the grooved flange of the 45 rail-head, so that not only are the ends of the rails firmly held in alinement, but the meeting ends of said grooved rail-flanges 50

are held from downward yielding or depression, as hereinbefore pointed out.

It is to be understood that the devices illustrated may be variously modified with respect to details of construction without departure from the spirit of my invention and I do not, therefore, desire to be limited to the specific features of structure and design illustrated except so far as the same may be pointed out in the appended claim as constituting part of my invention.

I claim as my invention:

In a rail-joint for street-railway rails, the combination of a joint bar consisting of a horizontal base-plate for supporting the rail ends, and longitudinal side members made integral with and extending upwardly from said base-plate at opposite sides of the rails, one of said side members having inwardly, downwardly and upwardly facing surfaces that are located adjacent to and are spaced from the web, base-flanges and heads of the rails, and all of which are longitudinally inclined from end to end of the said side members said side members being provided with bolt holes adapted to register with the bolt holes of the rail webs, a tapered wedge piece consisting of an upright member and integral base and top flange members; said upright and base and flange members being shaped on their inner surfaces to conform to the opposing faces of the webs, base-flanges and heads of the rails, and inclined on their outwardly, upwardly and downwardly facing surfaces to fit the inclined inwardly, downwardly and upwardly facing surfaces of the joint-bar, said wedge piece being provided with elongated bolt holes adapted to register with the bolt holes of the rail webs and joint bar and track bolts inserted through the bolt holes of said side members, the rail webs, and the wedge piece.

In testimony, that I claim the foregoing as my invention I affix my signature in the presence of two witnesses, this 28th day of February, A. D. 1913.

CHARLES CALVERT LAMB.
